FUEL INJECTION SYSTEM FOR INTERNAL COMBUSTION ENGINES

Heinrich Wälti, Winterthur-Wülflingen, Switzerland, assignor to Sulzer Frères, Société Anonyme, Winterthur, Switzerland

Application May 31, 1935, Serial No. 24,412
In Switzerland June 2, 1934

5 Claims. (Cl. 123—41)

This invention relates to fuel injection pumps for reversible internal combustion engines of the solid fuel injection type, and of the kind comprising a pump plunger which is reciprocated within a cylinder by a driving cam, the fuel charge being delivered under pressure.

The high pressures which obtain in fuel injection pumps of this type, and which may be some hundreds of atmospheres even in pumps supplying fuel to medium sized internal combustion engines, result in pressures of several tons on each pump plunger, this pressure having to be transmitted from the driving cam through the tappet roller to the pump plunger. In the case therefore of multi-cylinder engines wherein each engine cylinder is supplied from a pump cylinder, at least one of the pump plungers is at any given moment moving on its delivery stroke so that when the direction of operation of the engine is to be reversed it has hitherto been necessary either to cause relative adjustment of the cam and tappet roller of the pump plunger which is then moving on its delivery stroke, or to disengage the said tappet roller from its associated cam. In either case a large force, requiring a powerful transmission mechanism must be provided for the purpose of reversal. Further, in view of the high pressures occurring in the cylinders of fuel injection pumps the diameter of each pump plunger is limited whilst the quantity of fuel to be delivered is greater the smaller the speed of the engine at any given load. Owing to this limitation of the diameter of the pump plunger the plunger stroke, i. e. the lift of the driving cam, cannot be reduced below a given value more particularly if a precise regulation of the fuel charge to be delivered is to be obtained by varying the point in the plunger stroke at which delivery from the pump commences. Again, the injection angle, that is to say the crank angle prior to the top dead centre at which injection is to commence, is smaller the lower the speed of the engine and this angle must therefore be variable not only for forward but also reverse operation of the engine.

In a fuel injection pump according to the present invention the pump plunger is driven by a cam, of which one operating face comes into action for one direction of operation of the engine and the other operating face for the same kind of stroke of the plunger for the other direction of operation, and that control means are provided whereby beginning and end of the injection at the same load for each direction of operation of the engine are shifted to such posi-

tions of the crank-circle that the positions for one direction are symmetrical or approximately symmetrical to the positions for the other direction with respect to the dead centre, and that a favourable cam-life is possible also at low speeds. 5

Conveniently the control means consist of a space (or chamber) fitted in the path of the fuel under pressure, by means of which space by making use of the compressibility of the fuel the beginning of the fuel injection in the working 10 cylinder is delayed in comparison with the beginning of the delivery of fuel by the pump.

In the accompanying drawings,

Figure 1 is a vertical section through the cylinder of an internal combustion engine and fuel 15 injection pump embodying one construction according to the invention,

Figure 2 is an elevation taken from the same direction as Figure 1, with parts in section, showing the governor or operating mechanism for the 20 fuel pump control;

Figure 3 is a transverse sectional detail taken on an enlarged scale, on the line 3—3 of Figure 1, illustrating the sleeve drive;

Figure 4 illustrates the manner in which the 25 beginning and end of each injection is altered relatively to the upper dead centre position of the engine piston.

Figure 5 is a section through the fuel delivery conduit of another arrangement also according 30 to the invention.

Fig. 6 is an elevation of the engine showing the arrangement of the fuel lines.

Fig. 7 is a further modification of the engine with a different arrangement of fuel lines.

In the construction illustrated in Figure 1, the internal combustion engine 1 comprises a cylinder 2 in which a piston 3 is reciprocated from the engine crankshaft through a connecting rod 4. The fuel pump 5 is driven from the crank-shaft of the internal combustion engine 1, the fuel pump camshaft 6 being positively connected to the engine crankshaft by means of gearing (not shown). The camshaft 6 carries a fuel pump operating cam 7 having two operating surfaces 45 8 and 9, the surface 8 being operative for injection during forward operation of the engine whereas the surface 9 is operative for injection during reverse operation of the engine. The cam 7 operates a pump plunger 10 which reciprocates 50 within the cylinder of the pump 11, the cam engaging a tappet roller 12 at the lower end of the plunger which is furnished with a return spring 13.

Fuel is drawn through a suction pipe 14 and 55

suction port 15 into the working chamber 16 of the pump and is delivered from this working chamber through a delivery valve 17 to a delivery pipe 18. The fuel is delivered from the pipe 18 to a fuel injection valve 19 furnished with a needle 20 which, at the commencement of each injection, is raised from its seat by the pressure of the fuel in the pipe 18. A fuel chamber 20b is associated with the lower end of the needle 20 and is in communication with the fuel pipe 18. It will be understood that instead of arranging the valve 19 adjacent to the outlet of the fuel delivery pipe, this injection valve may be arranged nearer to the fuel pump 5 at some intermediate point in the length of the delivery pipe 18.

The camshaft 6 is coupled by gearing 20a and 20c to the governor shaft 20d with which is operatively associated a centrifugal governor 21, the sleeve 22 of which is engaged by one arm of a bell-crank lever 23, the other arm of which is connected to a crank 24 secured to a shaft 25. A second crank 26 on the shaft 25 is connected to a rack 27 which engages a toothed rim carried by a sleeve 28 furnished with projections 29 engaging the pump plunger 10. The plunger 10 is provided with an annular flange 29b having notches 29a designed to receive the projections 29 of the sleeve 28. The plunger 10 reciprocates within a liner sleeve 31, said liner being positioned within a sleeve or jacket 31a. The lower end of the jacket 31a is arranged to receive and partly house the spring 13. Thus, the governor 21 will turn the sleeve 28 and therefore the pump plunger 10 so as to vary the point in the delivery stroke of the plunger at which a control edge 30 on the plunger covers the fuel suction port 15. The quantity of fuel injected at each charge is thus automatically regulated by the governor 21.

Arranged between the pump cylinder and the fuel delivery pipe 18 is a fuel compression space or chamber 32 into which projects a displacer 33 which can be moved into or out of the fuel compression chamber 32 by means of a lever 34 having associated therewith a positioning quadrant 34a thereby adjusting the effective volume of the chamber 32. The displacement member 33 is biased upwardly by a spring member 34b. The needle 20 of the fuel injection valve 19 is loaded by a spring 36 the tension of which can be adjusted by means of a hand lever 38 which cooperates with a quadrant 37.

In Figure 4 the pump driving cam 7 is shown in the position in which the apex A of the cam coincides with the inner dead centre of the engine piston associated with the pump, this upper dead centre position being indicated by the crank 40. Since the forward and reverse operating surfaces 8 and 9 of the cam 7 meet at the apex A, the pump plunger 10 operated by the cam 7 will also be in its upper dead centre position, and delivery of the fuel pump under full load conditions will take place from the point B to the point C. If the cam 7 is to have the necessary lift, the point B must be considerably in advance of the inner dead centre of the engine piston since the end of delivery from the pump will take place at the point C when the apex A reaches the top dead centre position.

In low speed internal combustion engines the crank angle between the beginning of injection and the inner dead centre of the engine piston, is small so that injection commences somewhat later than the point B. With the arrangement illustrated in Figure 1 however, when delivery of fuel from the pump commences, the com-

pressibility of the fuel in the space 32 has the effect of retarding the beginning of injection from the point B to the point E and the end of injection from the point C to the point F, for forward operation of the engine. Similarly, for reverse operation of the engine, the beginning of injection is retarded from the point D to the point G whilst the end of injection is retarded from the point C to the point H. As will be seen from Figure 4 the retardation of the injection is the same whether the engine is to operate in the forward direction or in the reverse direction since the points E, G and H, F lie symmetrically with respect to the inner dead centre of the engine piston. Thus, for any given load the retardation in the fuel injection will be the same whether the engine is to operate in the forward or reverse direction.

In Figure 1, the plunger 10 is in its upper dead centre position. If now the engine is operating in the forward direction rotation of the cam-shaft 6 and cam 7 result in the tappet roller 12 running down the operating surface 8 of the cam 7, the plunger 10 being moved downwards by the spring 13. As soon as the control edge 30 on the plunger uncovers the suction port 15 fuel will be drawn into the working chamber 16 from the fuel supply pipe 14 until the plunger 10 reaches its bottom dead centre position, the tappet roller 12 then bearing against the concentric portion of the cam 7. As the cam 7 continues to rotate the delivery stroke of the plunger 10 will commence when the eccentric portion of the operating surface 8 commences to engage the tappet roller 12. As the plunger 10 moves upwards fuel is discharged from the working chamber 16 through the suction port 15 until the control edge 30 closes this suction port, after which the delivery of fuel from the working chamber 16 past the valve 17 commences.

Since the pressure in the space 32 at the end of the previous injection period corresponds to the closing pressure of the needle 20 it is necessary, in order for injection to commence, first to raise the pressure in the pipe 18 to the opening pressure of the needle 20. That is to say, injection will not commence until the pressure at the outlet end of the delivery pipe 18 reaches the opening pressure of the needle 20. The presence of the space 32, however, results in the degree to which the fuel on the delivery side of the pump can be compressed being increased, this increase being in accordance with the effective volume of the space 32. Thus, the greater the volume of the space 32 the later in the delivery stroke of the plunger 10 will the necessary pressure be reached in the delivery pipe 18 to raise the needle 20 of the injection valve 19. The commencement of injection is thus retarded as above described with reference to Figure 4.

When the apex A of the cam 7 engages the tappet roller 12 the plunger 10 reaches the end of its delivery stroke and delivery from the pump 5 is thus terminated, the valve 17 closing. The end of injection will, however, take place somewhat later, that is to say when the pressure in the space 32 and pipe 18 have fallen to a value which permits the spring 36 to move the needle 20 into its closed position. The end of injection is thus also retarded as described with reference to Figure 4.

Though the chamber 32 and displacer member 33 are both of constant cross-section, the form of the space 32 and/or of the displacer member 33 may be such as to avoid any sudden change

in the cross-section available for the flow of fuel from the pump to the delivery pipe 18. If such sudden change in cross-section is avoided the tendency to weaken or damp out the pressure wave in the fuel delivery system will be reduced. Further, instead of providing an enlarged compression space, such as the space 32, the retardation space may be provided by a pipe or conduit of substantially constant cross-section so that 10 each pressure impulse will be propagated through the column of fuel without the interference which would be introduced by a sudden variation in the cross-section of the passage through which the fuel flows to the fuel injection valve. A retardation space provided by a pipe or conduit of constant cross-section is, therefore, advantageous in that the desired retardation of the commencement of each injection relatively to the inner or top dead center of the engine piston 20 is determined actually in accordance with the velocity of propagation of each pressure wave which is in turn dependent on the length of the pipe or conduit, i. e., the length and compressibility of the said fuel column. The practically undamped propagation of the pressure wave 25 through the fuel column results in the velocity conditions provided by the operating surface of the cam being substantially fully utilized so that reliable opening of the fuel injection valve is ensured even at minimum load. In the case 30 of fuel pumps supplying multi-cylinder engines, each delivery pipe of the fuel pump may be made of the same length, as shown in Figure 8, even when some cylinders are farther from their associated injection pump cylinders than others. Alternatively, the pipes or conduits leading to cylinders which are nearer to their associated pump cylinders may have a greater internal diameter than the pipes or conduits which are 40 farther from their associated pump cylinders, as shown in Figure 9, so that, for example, each delivery pipe has the same capacity.

The displacer member 33 may, if desired, be automatically operated, as shown in Figure 2, 45 in accordance with a working value, such for example as the speed of or load on the engine and, with a view to ensuring effective injection at small loads, the tension of the loading spring 36 of the fuel injection valve 19 may be automatically controlled by a governor driven by the engine, for example, in the same manner as that shown for controlling the position of the plunger 33 in Figure 2.

Instead of varying the effective volume available for the fuel between the pump and the injection valve as described with reference to Figure 1, means may be provided whereby the effective length of the delivery conduit through which the fuel is delivered from the pump to the injection valve can be varied. One such arrangement is illustrated in Figure 5 in which a member 60 is arranged in the delivery system between the pump and the fuel injection valve, this member being furnished with a fuel delivery bore 61 with 55 which a conduit from the fuel pump communicates as at 61a. The opposite end of the bore 61 communicates as at 61b with a conduit in communication with the fuel valve. The member 60 has two pairs of conduits 62, 63 and 64, 65, the outer ends of the conduits 62, 63 being connected by a pipe 66, whilst the conduits 64, 65 are similarly connected by a pipe 66a. A rotary valve 67 is provided whereby communication between the conduit 61 and the conduits 64, 65 can either be cut off by moving the valve 67 to the

position III as shown in the drawings or, by setting the valve 67 in the position IV, the fuel can be caused to be deviated from the conduit 61 through the conduit 64 and conduit 65 to the fuel injection valve. The conduits 62, 63 can similarly be connected to the conduit 61 by means of a rotary valve 68. Thus, by moving either or both the valves 67, 68 into the position IV the effective length of the delivery conduit is increased and the time required to compress the fuel lying between the pump and the injection valve is increased, thereby increasing the retardation of the commencement and end of each injection as described with reference to Figure 4. All the connections to the member 60, that is 10 to say for example as the connection between each end of the pipe 66 and the conduits 62 and 63, are such that sealing of the joint is effected at the inner end of the connection so that the bores of the conduits which are connected together are directly in registration and sudden increases in the internal diameter of the conduits through which the fuel flows is avoided so that the pressure wave of the fuel flow is not weakened by any sudden enlargement. 15

The rotary valves 67 and 68 may be automatically controlled in accordance with a working value of the internal combustion, say, the speed of or load on the engine. Thus, for example, the valves 67 and 68 may be automatically operated 20 by a governor driven by the engine, their handle levers 69 being connected to a governor in a manner similar to that of lever 34, as shown in Figure 2.

The invention is advantageous in that when 35 the direction of operation of the engine is reversed each tappet roller of the pump can remain in engagement with its associated operating cam so that difficulties in reversal, due to the large forces which are applied to the plunger, 40 do not arise. Further, the quantity of fuel injected at each charge can be adjusted relatively to the end of injection by varying the point in the plunger stroke at which delivery from the pump commences. At small loads therefore the commencement of injection is shifted relatively 45 to the inner dead centre position of the engine piston. Even at low loads injection will take place at a high pressure and a high temperature within the working chamber of the engine cylinder so that ignition of the fuel charge is ensured. 50

Since the cam for driving each pump plunger has operating surfaces for the two directions of operation of the engine respectively, when the 55 crank angle between the beginning of the injection and the inner dead center of the engine piston is to be small, say, for a low speed engine, the lift of the cam must be short. With a view to reducing the tendency for shocks to be imparted from the cam to its associated tappet roller, each operating surface of the cam may be tangential to the concentric part of the cam. The invention is also advantageous in that it makes it possible to avoid undesirable low-lift 60 cams which would not only involve excessive pressures on the pump plunger but would also tend to prevent fine regulation of the quantity of fuel injected by adjusting the point in the delivery stroke of the plunger at which the pump commences to deliver fuel. 65

The control of the member 33 by the lever 34 may be manual, as shown in Figure 1, or may be automatic, as shown in the modification of Figure 2. As described in connection with Figure 1 70

the shaft 25 is moved in response to the movement of the governor 21. This movement of the shaft 25 is effective, as above described, to move the rack 27. The governor 21 may be connected so as to operate the lever 34 directly, if it is desired to provide an automatic control and movement for the member 33. Thus as shown in Figure 2, a link 14 is secured at one end to the outer end of the bell crank lever 23, which 10 is itself in contact with the sleeve 22 of the governor 21. The other end of the link 14 is secured to the lever 34 and thus movement of the governor is effective through the bell crank lever 23, the link 14 and the lever 34 automatically to 15 move the member 33. It is to be understood that this automatic connection, whereby the governor moves and controls the position of the member 33 may or may not be used, and the control of this member may thus be either manual or 20 automatic.

As illustrated in Figure 6, 1 is the engine, 11 is the multicylinder pump. A conduit 10 runs to each cylinder from the pump. These conduits are of constant and identical cross section and 25 are shaped so that irrespective of the actual distance from the pump to each cylinder, the length of the conduit and the space within the conduit is, therefore, identical for each cylinder.

The engine shown in Figure 6 appears again 30 in Figure 7, but instead of providing conduits from the pump to each cylinder of constant diameter and length, the conduits are of different diameters and different lengths. Thus the conduit 70 is the shortest, but is of the greatest diameter. The conduit 72 is somewhat longer and of somewhat less diameter than the conduit 71 and the conduit 73 is the longest and is of the least diameter. Thus the space enclosed within 35 each conduit between the pump and the cylinder to which that conduit leads is the same for all of the conduits and in the form of the device shown in Figures 6 and 7, all delivery pipes to the various cylinders have the same capacity.

As above pointed out, the retardation space 40 might include a special space such as the space 45 32 of Figure 1, or it might include a fuel conduit between the pump and fuel valve of variable length, as shown in Figure 5, or it might include a combination of the two. In general, therefore, the retardation space is positioned somewhere in 50 the path which the fuel travels in moving from the pump to the fuel valve or injection valve past which fuel is discharged toward or into the cylinder.

I claim:

1. In combination a fuel injecting pump for reversible internal combustion engines with airless injection of fuel, a pressure actuated injection valve and a fuel line connecting said valve with said pump, a cam having adjoining symmetrical operating faces for driving said pump, control means for retarding the period of injection with reference to the period of the delivery of fuel by said pump, said control means comprising conduits in controlled communication with the fuel line and of uniform cross-sectional area substantially equal to the cross-sectional area of said fuel line whereby pressure waves of fuel flow are not weakened by sudden enlargements of the conduit.
2. In combination a fuel injecting pump for reversible internal combustion engines with airless injection of fuel, a pressure actuated injection valve and a fuel line connecting said valve with said pump, a cam having adjoining sym-

metrical operating faces for driving said pump, control means for retarding the period of injection with reference to the period of the delivery of fuel by said pump, said control means comprising conduits of uniform cross-sectional area 5 substantially equal to the cross-sectional area of the fuel line and adjustably jointed thereto, each joint for the conduits being such that the two conduits connected together are in direct registration, thereby avoiding an enlargement in the 10 cross section at the joint whereby pressure waves of fuel flow are not weakened by said sudden enlargement.

3. In combination, with a reversible two-stroke cycle internal combustion engine a cylinder, a piston, a crank shaft, a connection between the piston and crank shaft, a fuel pump comprising a cylinder and a pump plunger, an injection valve, a fuel conduit between the pump cylinder and injection valve, a drive for the pump plunger actuated by movement of the engine crank shaft, the drive being so arranged and proportioned that the pump plunger is at inner dead center at approximately the time that the engine piston is at inner dead center, and a cam adapted to 25 actuate said pump plunger, said cam being provided with a pair of symmetrical faces, the upper ends of said faces adjoining each other, the capacity of the conduit between the pump cylinder and injector being such that the injection 30 period is delayed with respect to the movement of the pump plunger and delivery of fuel from the injection valve to the engine cylinder continues a predetermined time after the pump plunger has reached its inner dead center and 35 after discharge of fuel from the pump cylinder to the conduit has terminated, and means for varying the capacity of said conduit.

4. In combination, with a reversible two-stroke cycle internal combustion engine a cylinder, a piston, a crank shaft, a connection between the piston and crank shaft, a fuel pump comprising a cylinder and a pump plunger, an injection valve, a fuel conduit between the pump cylinder and injection valve, means controlling the passage of fluid from the pump cylinder to the conduit, said means comprising a valve, adapted to open upon pressure from the pump cylinder to permit passage of fuel into the conduit, and adapted to close automatically to prevent return flow of fuel into the cylinder, a drive for the pump plunger actuated by movement of the engine crank shaft, the drive being so arranged and proportioned that the pump plunger is at inner dead center at approximately the time that the engine piston is at inner dead center, and a cam adapted to 40 actuate said pump plunger, said cam being provided with a pair of symmetrical faces, the upper ends of said faces adjoining each other, the cam faces being related to the crank shaft of 45 the engine in such manner that when the engine piston and the pump plunger are at approximately their respective inner dead centers, the peak of the cam at which the upper ends of said cam faces join, is in contact with the driving 50 means for actuating the said plunger, the capacity of the conduit between the pump cylinder and injector being such that the injection period is delayed with respect to the movement of the pump plunger and delivery of fuel from the injection valve to the engine cylinder continues a predetermined time after discharge of fuel from the pump cylinder to the conduit has terminated, and means for varying the capacity of said conduit.

5. In combination, with a reversible two-stroke cycle internal combustion engine a cylinder, a piston, a crank shaft, a connection between the piston and crank shaft, a fuel pump comprising a cylinder and a pump plunger, an injection valve, a fuel conduit between the pump cylinder and injection valve, means controlling the passage of fluid from the pump cylinder to the conduit, said means comprising a valve, adapted to open upon 10 pressure from the pump cylinder to permit passage of fuel into the conduit, and adapted to close automatically to prevent return flow of fuel into the cylinder, a drive for the pump plunger actuated by movement of the engine crank shaft, 15 the drive being so arranged and proportioned that the pump plunger is at inner dead center at approximately the time that the engine piston is at inner dead center, and a cam adapted to actuate said pump plunger, said cam being provided with a pair of symmetrical faces, the upper 20 ends of said faces adjoining each other, the cam faces being related to the crank shaft of the engine in such manner that when the engine
- piston and the pump plunger are at approximately their respective inner dead centers, the peak of the cam at which the upper ends of said cam faces join, is in contact with the driving means for actuating the said plunger, the capacity of the conduit between the pump cylinder and injector being such that the injection period is delayed with respect to the movement of the pump plunger and delivery of fuel from the injection valve to the engine cylinder continues a 10 predetermined time after the pump plunger has reached its inner dead center and after discharge of fuel from the pump cylinder to the conduit has terminated, and means for varying the capacity of said conduit, and additional means 15 actuated at varying speeds in conformity with variation in the engine speed for controlling the movement of said capacity varying member to control the capacity of said conduit automatically in conformity with variations in the engine 20 speed.

HEINRICH WÄLTI.
